TRIANGULAR CARTONS

Leonard A. Wheeler, 209 Pinewood Trail, Port Credit,
Ontario, Canada
Filed Dec. 7, 1959, Ser. No. 857,811
8 Claims. (Cl. 229—22)

This invention relates to triangular cartons. More particularly the invention relates to a blank from which triangular cartons can be made, methods of assembling the blank to form cartons, and the resulting cartons which are of triangular cross-section when erected and are made in a flattened condition so that they may be shipped in their flattened condition and easily erected by the user.

Collapsible triangular cartons are already known but it is believed that all such cartons as are known suffer from one or both of the following disadvantages. The first disadvantage is that no method has heretofore been developed for assembling the cartons on such automatic machinery, e.g., right-angled gluers, as are conventional in the art; the cartons have thus been assembled by hand which is slow and expensive. The second disadvantage is that the bottom of the carton, which has been arranged to come into position automatically as the carton is erected from its flattened condition, has not been provided with any locking means so that the bottom has had a tendency to move into the interior of the carton after the latter has been erected. Since the bottom is used to hold the carton in its erected position it is obviously desirable that the bottom should be locked in position when the carton is erected.

One of the objects of the invention is to provide a carton of triangular cross-section which may be shipped and stored in a flattened condition and which is arranged so that one end thereof is locked in position when the carton is erected from its flattened condition.

A further object of the invention is to provide a blank from which such a carton may be assembled.

A still further object of the invention is to provide a method whereby collapsible triangular cartons may be assembled by fully automatic machinery such as right-angled gluers.

The invention will be described by way of example with reference to the accompanying drawings, in which:

FIGURE 1 is a plan view of a blank according to the invention for making a triangular carton,

FIGURES 2, 3 and 4 show consecutive stages in the assembly of the blank of FIGURE 1,

FIGURE 5 is a perspective view of the carton resulting from the blank of FIGURE 1 and the stages of FIGURES 2 to 4 as it is being erected,

FIGURE 6 is a perspective view of the carton of FIGURE 5 fully erected and partly broken away to show the locking arrangement of the carton bottom,

FIGURE 7 is a view similar to FIGURE 3 showing a corresponding stage in a modified method of assembling the blank of FIGURE 1, and

FIGURE 8 is a perspective view of a carton resulting from said modified method.

Referring now to FIGURE 1, the carton blank comprises a sheet of paperboard or the like cut and scored to provide a first side wall portion 10 defined by scores 11 and 12; a second side wall portion 13 defined by scores 12 and 14; and a third side wall portion 15. The first, second and third side wall portions are arranged in seriate side-by-side relation. A glue tab 16 is integral with the first side wall portion 10 and the latter is bisected by a score 17 parallel to its length to provide two equal panels 10a and 10b.

A first end flap 18 extends from one end of the second side wall portion 13. The end flap comprises an equilateral, triangular part 19 having as base a score 20 at

2

the end of the second side wall portion. Springing from an edge of the triangular part 19 is a first extension 21 adjacent to the apex of the triangular part; the extension 21 and the part 19 are separated by a score 22. It will be noticed that the first extension 21 is on the edge of the triangular part 19 remote from the glue tab 16. A second extension 23 extends from the other edge of the triangular part 19 and is separated from the latter by a score 24.

10 A second end flap 25 extends from the third side wall portion 15 and is scored along a line 26 which lies at an angle α of substantially 30° to the end of the third side wall portion 15 defined by the score 27. The score 26 divides the second end flap 25 into an inner portion 28 lying between the score lines 26 and 27 and an outer portion 29. The second end flap is cut away at 30 for a purpose which will hereinafter be described.

The glue tab 16 is provided, at its end adjacent to the end flaps 18 and 25, with a recess indicated generally at 31 which is defined by an inclined edge 32 and a straight edge 33. As will be described hereinafter, the straight edge 33 mates with an edge 34 on the first extension 21 and the inclined edge 32 of the recess 31 mates with an edge 35 on the first extension 21.

25 The end flaps 25, 18 are designed to close one end of the carton automatically as the carton is erected and as will hereinafter be described. The construction of flaps at the other end of the carton does not form part of the present invention and therefore no flaps have been shown in the drawings. It will be understood by one skilled in the art that any convenient top closure can be employed or it can be omitted if desired.

In the assembly of the blank to form the carton, the initially flat blank as shown in FIGURE 1 is passed along a first straight line path in the direction of the arrow 36. While the blank is passing along this first straight line path, the end flaps 18 and 25 are folded to overlie the second and third side wall portions 13 and 15 respectively. Furthermore, the outer portions 29 of the second end flap 25 is folded along the score 26 to overlie the inner portion 28 of the second end flap. At the end of the passage of the blank along the first straight line path, the blank has assumed the form shown in FIGURE 2.

The blank in the form shown in FIGURE 2 is then passed along a second straight line path in the direction of the arrow 37; the second path is perpendicular to the first path. As the blank passes along the second straight line path, the first side wall portion 10 is folded about the score 17 so that the panel 10a is caused to overlie the panel 10b and so that the glue tab 16 partially overlies the second extension 23 and the triangular part 19 as shown in FIGURE 3. After this fold has been made, the glue tab 16 and the outer portion 29 of the second end flap are provided with spots of adhesive 38, 39 respectively by means of a roller in known manner. As a final operation, the third side wall portion 15 is folded over about the score 14 to overlie the second side wall portion 13. Upon this final folding the glue tab 16 is adhered to the third side wall portion 15 and the outer portion 29 of the second end flap 25 is adhered to part of the outer surface of the triangular part 19 of the first end flap. The bottom end of the carton in its final flattened form is shown in FIGURE 4.

The flattened carton of FIGURE 4 is erected by applying pressure in the directions of the arrows 40 and 41 in FIGURE 5 to the scores 14 and 17. As the side wall portion 10 flattens it pushes apart the remote edges of the second and third side wall portions 13 and 15 which pivot about the score 14 until the carton assumes a triangular cross-section. As the side wall portions 13 and 15 move apart, the outer portion 29 of the second end flap which is secured to the triangular part 19 of

the first end flap will draw the triangular part into a position in which it is perpendicular to the side wall portions. When the carton is fully erected, as shown in FIGURE 6, the second end flap 25 is outside and parallel to the triangular part 19 of the first end flap and both end flaps are perpendicular to the side wall portions.

As the triangular part 19 is moved into a position in which it is perpendicular to the side wall portions, the first and second extensions 21 and 23 will come into contact with the third and first side wall portions 15 and 10 respectively and will be bent until they lie perpendicular to the triangular portion 19 as shown in FIGURE 6. Referring now to this figure, it will be seen that the first extension 21 has been received in the recess 31 at the end of the glue tab 16. In this position, the edges 34, 35 of the first extension 21 mate with the edges 33 and 32 respectively of the recess 31. The first extension 21 is maintained in the recess 31 by the natural resilience of the paperboard and once it has been received in the recess it will be seen that it will prevent the triangular part 19 of the first end flap from moving inwardly towards the interior of the carton.

The triangular part 19 is dimensioned to substantially close the end of the carton and therefore it holds the side walls in their open position so long as it is maintained perpendicular to the walls by means of the lock constituted by the recess 31 and the extension 21. In the fully erected position of FIGURE 6, the second extension 23 is pressed against the first side wall portion 10 and forms a seal against that side wall portion thus preventing the escape of the contents of the carton should these be of a pulverulent or similar nature. Moreover, the extension 23 helps to flatten the side wall portion 10 as the carton is erected. The second end flap is cut away at 30 so that, as the blank is assembled, the end flap will not be caused to overlie the glue tab 16 to an extent sufficient to prevent erection of the carton.

It will be seen that the blank of FIGURE 1 may be easily assembled an a conventional right-angled gluer in which, as the blank is being passed in one direction, the end flaps may be folded in directions perpendicular to the direction of movement and, as the blank is moved in a second direction the side wall portions may be folded in to complete the assembly of the carton. Moreover, when the carton is assembled, the bottom is locked in position by means of the extension 21 and the notch 31 and the bottom of the carton is sealed where it might be likely to leak by means of the second extension 23 of the first end flap. In the embodiment so far described, when the carton is assembled, the inner and outer portions 28, 29 of the second end flap lie substantially in the same plane which makes for a very neat appearance. As mentioned above, any convenient top closure may be provided.

Referring now to FIGURE 7, this shows an alternative step in a method of folding the blank of FIGURE 1 to make a triangular carton similar to that hereinbefore described. FIGURE 7 indicates a stage of folding of the blank corresponding to the stage shown in FIGURE 3 for the first embodiment. The only differences between the two stages is that in FIGURE 7 the outer portion 29 of the second end flap 25 has not been folded to overlie the inner portion 28 of the end flap and thus remains in the same plane therewith. Glue spots 42 are applied to the outer portion 29 at the same time as glue spots 38 are applied to the glue tab 16 and upon folding over of the third wall portion 15 about the score line 14, the outer portion 29 is adhered to the outer surface of the triangular part 19 of the first end flap. The cut-out 30 in this case is also provided to clear the glue tab 16 as described in the previous embodiment.

The carton formed by this modified method is erected in the same way as the carton previously described, i.e. the score lines 14 and 17 are pushed towards one an-

other. However, due to the different gluing of the outer portion 29 of the second end flap, the second end flap will be folded over on the score 26 when the carton is assembled as shown in FIGURE 8 so that the outer portion 29 of the second end flap lies between the inner portion 28 of the second end flap and the triangular part 19 of the first end flap. The locking of the triangular part 19 is identical to that previously described.

If the second extension 23 is omitted, the glue tab 16 could be made integral with the third side wall portion 15 and in that case the extension 21 would be formed on the edge of the part 19 remote from the glue tab. Also the final assembly step is different in that the third side wall portion 15 would be folded over prior to folding of the first side wall portion 10.

The invention provides a carton blank which may be folded by automatic machinery, such as a right-angled gluer, to form a collapsible triangular carton. The carton so made has an end structure which automatically locks as the carton is opened and prevents the end flap from moving inwardly into the interior of the carton. Moreover, in the preferred embodiment, the end flap has an extension which prevents seepage of the contents of the carton through the end closure. Furthermore, the invention provides a method whereby a blank according to the invention may be folded on an automatic machine to produce the carton.

It will be understood that the forms of the invention herewith shown and described are preferred examples and that various modifications may be carried out without departing from the spirit of the invention or the scope of the appended claims.

What I claim as my invention is:

1. A carton blank comprising a sheet of paperboard or the like cut and scored to provide first, second and third side wall portions in seriate side-by-side relation, a glue tab integral with one of said first and third side wall portions and arranged to be secured to the other of said first and third side wall portions when the carton is assembled, a score bisecting said first side wall portion parallel to the length thereof, first and second end flaps extending from corresponding ends of the second and third side wall portions respectively, the first end flap comprising an equilateral triangular part having as base the end of the second side wall portion, and an extension of said triangular part springing from the edge thereof which is remote from the glue tab, said extension being adjacent to the apex of the triangular part, the second end flap being scored along a line lying at substantially 30° to the end of the third side wall portion and intersecting said end adjacent to the score between the second and third side wall portions, and the glue tab having a recess at the end thereof which is adjacent to said end flaps, said recess being dimensioned to receive said extension when the carton is assembled.

2. A carton blank comprising a sheet of paperboard or the like cut and scored to provide first, second and third side wall portions in seriate side-by-side relation, a glue tab integral with said first side wall portion and arranged to be secured to the third side wall portion when the carton is assembled, a score bisecting said first side wall portion parallel to the length thereof, first and second end flaps extending from corresponding ends of the second and third side wall portions respectively, the first end flap comprising an equilateral triangular part having as base the end of the second side wall portion, a first extension of said triangular part springing from the edge thereof which is remote from the glue tab, said extension being adjacent to the apex of the triangular part, and a second extension along said other edge of the triangular part and arranged to lie within said first side wall portion when the carton is assembled, the second end flap being scored along a line lying at substantially 30° to the end of the third side wall portion and intersecting said end adjacent to the score between the second and third side

wall portions, the glue tab having a recess at the end thereof which is adjacent to said end flaps, said recess being dimensioned to receive said first extension when the carton is assembled.

3. A carton of triangular cross-section comprising first, second and third side walls, said first side wall being bisected by a score parallel to the length of the carton; a glue tab integral with one of said first and third side walls and secured to the other of the first and third side walls; a first end flap extending from an end of the second side wall perpendicular thereto and having an equilateral triangular part of a size to substantially close one end of the carton and having as base the end of the second side wall; a second end flap extending from an end of the third side wall corresponding to said end of the second side wall, the second end flap lying outside the first end flap and being scored along a line lying at substantially 30° to said end of the third side wall whereby said second end flap is divided into an inner portion lying between said line and said end of the third side wall and an outer portion which is secured to the outer surface of the first end flap; and an extension of said triangular part adjacent to the apex thereof and extending perpendicular to said triangular part to lie adjacent to said other of said first and third side walls; said glue tab having, at an end thereof adjacent to said end flaps, a recess dimensioned to receive said extension, engagement of the extension in the recess preventing movement of the first end flap into the interior of the carton.

4. A carton according to claim 3, wherein the inner and outer portions of the second end flap lie in substantially the same plane.

5. A carton according to claim 3, wherein the outer portion of the second end flap lies between the inner portion of the second end flap and said first end flap.

6. A carton of triangular cross-section comprising first, second and third side walls, said first side wall being bisected by a score parallel to the length of the carton; a

glue tab integral with the first side wall and secured to the third side wall; a first end flap extending from an end of the second side wall perpendicular thereto and having an equilateral triangular part of a size to substantially close one end of the carton and having as base the end of the second side wall; a second end flap extending from an end of the third side wall corresponding to said end of the second side wall, the second end flap lying outside the first end flap and being scored along a line lying at substantially 30° to said end of the third side wall whereby said second end flap is divided into an inner portion lying between said line and said end of the third side wall and an outer portion which is secured to the outer surface of the first end flap; a first extension of said triangular part adjacent to the apex thereof and extending perpendicular to said triangular part to lie adjacent to the third side wall; and a second extension along the edge of said triangular part adjacent to the first side wall and extending perpendicular to said triangular part to lie against said first side wall; said glue tab having, at an end thereof adjacent to said end flaps, a recess dimensioned to receive said first extension, engagement of the first extension in the recess preventing movement of the first end flap into the interior of the carton.

25 7. A carton according to claim 6, wherein the inner and outer portions of the second end flap lie in substantially the same plane.

8. A carton according to claim 6, wherein the outer portion of the second end flap lies between the inner portion of the second end flap and said first end flap.
